UNITED STATES PATENT OFFICE.

JULIUS BRENZINGER, OF FAIRFIELD, CONNECTICUT, ASSIGNOR TO THE MAX AMS MACHINE COMPANY, OF BRIDGEPORT, CONNECTICUT, A CORPORATION OF NEW YORK.

COVER-FEEDING MEANS.

Original application filed October 25, 1923, Serial No. 670,682. Divided and this application filed December 24, 1924. Serial No. 757,818.

This invention relates generally to blank feeding devices and has more particularly reference to a device for feeding covers or bottoms from a stack to a seaming machine.

5 This application is a division of application Ser. No. 670,682 filed October 25, 1923.

In the accompanying drawings the invention is shown in a concrete form in which:

10 Fig. 1 is a top plan view of the cover feed mechanism and adjacent elements.

Fig. 2 is a vertical longitudinal sectional view on the plane of line 2—2 of Fig. 1.

15 Fig. 3 is a horizontal sectional view on the plane of line 3—3 of Fig. 2.

Fig. 4 is a horizontal sectional view on the plane of line 4—4 of Fig. 2.

20 Fig. 5 is a horizontal sectional view on the plane of line 5—5 of Fig. 2.

Fig. 6 is a vertical sectional view on the plane of line 6—6 of Fig. 5.

25 Fig. 7 is a horizontal sectional view on the plane of line 7—7 of Figs. 2 and 6.

Fig. 8 is a vertical sectional view on the plane of line 8—8 of Fig. 1.

30 Fig. 9 is a detail perspective view of one of the "throw-out" dogs of the clutch.

Fig. 10 is a detail perspective view of the clutch pin of the clutch.

35 Fig. 11 is a transverse vertical sectional view on the plane of line 11—11 of Fig. 1.

Fig. 12 is a detail sectional view on the plane of line 12—12 of Fig. 11.

1 indicates a body or container to which a cover or bottom as 2 is to be united. As

35 shown in Fig. 11 the bodies come down an inclined plane 79 and are received by a dial 80 which delivers them to pockets 24 of a rotatable turret 11. Bottoms 2 are contained in a stack 84 from which they are separated

40 and carried by suitable means to inclined dial 104 which latter conveys said covers by means of fingers 144 and turns them edge-wise into guide 145, from which they pass to pockets 25, adjacent pockets 24, in the

45 turret. Suitable mechanism, not here described but generally indicated by reference character 4, unites the bodies and covers. Suffice it to say that the bodies and covers are clamped by suitable work-holding means

50 in the turret and that a number of bodies and covers are acted upon at the same time during the revolution of the turret in the

manner described in application Ser. No. 670,682.

84 indicates a hopper for the covers at the 55 lower open ends of which are a plurality of feeding-out rollers 85 (here three in number) having spiral grooves 86 in their outer circumference. These rollers serve to support the stack and also, by their rotation, to 60 feed out the covers singly in a manner well understood until the cover drops on table 87 between the arms of starwheel 88 which conveys it out of the plane of the hopper. Each feeding-out roller 85 is carried by an upright 65 stem 89 suitably supported in the framework and each stem carries a pinion 90 engaging a central gear 91 also mounted in the framework. One of the pinions 90, marked 90^a, drives gear 91 and the latter in 70 turn drives the two other pinions 90. Pinion 90^a also drives starwheel 88 by means of pinion 92 engaging internal gear 93 on said starwheel. Gear 90^a receives its motion from pinion 94, loosely mounted on upright 75 shaft 95, by means of pins 96. Pinion 94 is driven by gear 97 and moving with the latter gear is pinion 98 imparting motion to a train of gears 99, 100, 101 and bevels 102 and 103 by means of which latter inclined 80 dial 104 is driven. Gear 97 and pinion 98 are slidably mounted in the bushing or actuating member 105 so that an upward movement of these parts will disengage gear 85 94 from gear 98 from gear 99 thereby stopping dial 104, starwheel 88 and feeding-out rollers 85. Fixed to the underside of pinion 98 is one or more cam dogs or teeth 106 that are engaged by corresponding cam dogs or teeth 107 on rotating 90 clutch member 108, said rotating clutch member being seated in stationary member 109 carried by the framework. It will be evident that, if any part of the cover feed mechanism jams and the parts stop rotating, 95 dog 107 will lift pinion 98 and gear 97 by reason of the inclined surfaces on dogs 106 and 107 and thus stop rotation of the parts of the cover feeding means. When this happens, handle 110 will be moved downward by turning on center 111 because handle 110 has two arms 112 that engage in groove 113 of the sliding member carrying pinion 98 and gear 94. Thereupon latch 114

will fall and will retain the parts in the position to which they have been moved, and the cover feeding mechanism will be stopped until released by hand. Clutch member 108 is driven from gear 115 by means of clutch pin 116 seated in member 108 and normally pressed by spring 117 into an opening in member 118 which latter is carried by gear 115. Gear 115 is driven from gear 119 mounted on shaft 120 carrying gear 23 which latter receives its motion from idler 22. If clutch pin 116 is withdrawn from engagement with member 118 rotation of the parts of the cover feeding mechanism will cease. To accomplish this the following construction is used: Pivotedly mounted on stationary member 109 at pivot point 123 are two arms 124 carrying trip lever 125 and having also two pins 126 that normally enter openings in reciprocating dogs 127 mounted in slides 128 of stationary member 109. Springs 129 bearing on member 109 and connected to said dogs 127 urge the dogs inwardly but the inward movement is prevented by pins 126. When trip lever 125 is lifted, pins 126 disengage the dogs and these fly inward and one of the cam surfaces 130 thereof engages cam surface 131 of clutch pin 116 when the latter comes opposite one or the other of said dogs 127 with the result that the clutch pin is lifted and power is no longer transmitted by gear 115 to member 108 and the cover feeding ceases to operate. Member 118, however, continues its rotation and restoring cams 132 carried thereby act on rolls 133 of dogs 127 and retracts said dogs thereby allowing spring 117 to restore clutch pin 116 to engagement with member 118 and pins 126 descend into engagement with the dogs and hold them in their restored position. The driving connection is thereby reestablished. Any suitable means may, of course, be used for lifting and lowering trip lever 125 and it may be done by hand but, in the present instance, the trip lever is controlled from the can body in feeding mechanism by the following means: Supported in front of body infeed dial 80 is a detector arm 134. This arm is pivoted at 135. So long as bodies 1 pass in a constant stream this arm is held outwardly by said bodies but if a body is missing it falls inwardly by gravity. Connected to this detector arm is one arm 136 of a bell crank, hung on rod 137, the other arm 138 of which is secured to connection 139 which latter extends to and is secured to one arm of a bell crank mounted on bracket 141 the other arm 142 of which comes under trip lever 125. When, therefore, a body is missing trip lever 125 is lifted, the action being facilitated by spring 143, and the cover feeding mechanism is stopped, and when a body is again fed the cover feeding mechanism starts again.

A cover is separated from the stack by roller 85 and is thereby fed to the starwheel 88. This starwheel carries the cover to fingers 144 of inclined dial 104 which conveys the cover and turns it edgewise into guide 145. From guide 145 the cover passes into groove 25 of one of the pockets of the turret where it is then associated with a body in the manner previously described.

I claim:

1. A blank separating and feeding device comprising: a blank hopper, means for separating blanks one by one from the hopper, a blank feeding device to receive blanks from the hopper, an actuating member, transmission means from the actuating member to the separating means, transmission means from the actuating member to the feeding device, and means whereby a choke in the feeding means acts to disconnect the transmission means of both the separating means and the feeding means.

2. A blank separating and feeding device comprising: a blank hopper, means for separating blanks one by one from the hopper, a blank feeding device to receive blanks from the hopper, an actuating member, transmission means from the actuating member to the separating means, transmission means from the actuating member to the feeding device, means whereby a choke in the feeding means acts to disconnect the transmission means of both the separating means and the feeding means, a body feeding device, and means for stopping the movement of the actuating member when a body is absent in the body feeding device.

3. A blank separating and feeding device comprising: a blank hopper, means for separating blanks one by one from the hopper, a blank feeding device to receive blanks from the hopper, an actuating member, transmission means from the actuating member to the separating means, transmission means from the actuating member to the feeding device, means whereby a choke in the feeding means acts to disconnect the transmission means of both the separating means and the feeding means, a clutch for driving the actuating member, a body feeding device, and means for disconnecting the clutch when a body is absent in the body feeding device.

4. A blank separating and feeding device comprising: a blank hopper, means for separating blanks one by one from the hopper, a blank feeding device to receive blanks from the hopper, a rotatable actuating member slidably mounted, two gears carried by said actuating member, a train of gears from one of said gears to the separating means, a train of gears from the other of said gears to the blank feeding device, and driving connections for the actuating member to lift the latter and thereby to disconnect the two gears from the two trains of gears upon

- the occurrence of a choke in the blank feeding means.
5. A blank separating and feeding device comprising: a blank hopper, means for separating blanks one by one from the hopper, a blank feeding device to receive blanks from the hopper, a rotatable actuating member slidably mounted, two gears carried by said actuating member, a train of gears from one of said gears to the separating means, a train of gears from the other of said gears to the blank feeding device, driving connections for the actuating member to lift the latter and thereby to disconnect the two gears from the two trains of gears upon the occurrence of a choke in the blank feeding means, a body feeding device, and means for stopping rotation of the actuating member when a body is absent in the body feeding device. 35
- 10 6. A blank separating and feeding device comprising: a blank hopper, means for separating blanks one by one from the hopper, a blank feeding device to receive blanks from the hopper, a rotatable actuating member slidably mounted, two gears carried by said actuating member, a train of gears from one of said gears to the separating means, a train of gears from the other of said gears to the blank feeding device, driving connections for the actuating member to lift the latter and thereby to disconnect the two gears from the two trains of gears upon the occurrence of a choke in the blank feeding means, and an automatically operated latch to retain the actuating member in its elevated position. 40
- 15 7. A blank separating and feeding device comprising: a blank hopper, means for separating blanks one by one from the hopper, a blank feeding device to receive blanks from the hopper, a rotatable actuating member slidably mounted, two gears carried by said actuating member, a train of gears from one of said gears to the separating means, a train of gears from the other of said gears to the blank feeding device, driving connections for the actuating member to lift the latter and thereby to disconnect the two gears from the two trains of gears upon the occurrence of a choke in the blank feeding means, a clutch for driving the actuating member, a body feeding device, and means for disconnecting the clutch when a body is absent in the body feeding device. 45
- 20 8. A blank separating and feeding device comprising: a blank hopper, means for separating blanks one by one from the hopper, a blank feeding device to receive blanks from the hopper, a rotatable actuating member slidably mounted, two gears carried by said actuating member, a train of gears from one of said gears to the separating means, a train of gears from the other of said gears to the blank feeding device, driving connections for the actuating member to lift the latter and thereby to disconnect the two gears from the two trains of gears upon the occurrence of a choke in the blank feeding means, a clutch for driving the actuating member, a body feeding device, and means for disconnecting the clutch when a body is absent in the body feeding device. 50
- 25 9. A blank separating and feeding device comprising: a blank hopper, means for separating blanks one by one from the hopper, a blank feeding device to receive blanks from the hopper, a rotatable actuating member slidably mounted, two gears carried by said actuating member, a train of gears from one of said gears to the separating means, a train of gears from the other of said gears to the blank feeding device, driving connections for the actuating member to lift the latter and thereby to disconnect the two gears from the two trains of gears upon the occurrence of a choke in the blank feeding means, a clutch for driving the actuating member, a body feeding device, and means for disconnecting the clutch when a body is absent in the body feeding device. 55
- 30

Signed at New York, in the county of New York and State of New York, this 17th day of December, 1924.

JULIUS BRENZINGER.
